ENGINE HOUSING

Rustan Lange, Jonkoping, Sweden, assignor to Kendale Industries, Inc., Independence, Ohio

Filed Oct. 16, 1969, Ser. No. 19,588

Term of patent 14 years

Int. Cl. D15—01

U.S. Cl. D77—1

FIG. 1 is a perspective view of an engine housing embodying my design;

FIG. 2 is a side view of the same, the opposite side being similar;

FIG. 3 is a front end view of the same;

FIG. 4 is a top plan view of the same; the bottom being plain; and

FIG. 5 is a rear end view of the same.

I claim:

The ornamental design for an engine housing, substantially as shown and described.
